Max Weil

Application June 30, 1950, Serial No. 10,847

Term of patent 14 years

(Cl. D44—15)

To all whom it may concern:

Be it known that I, George A. Baker, a citizen of the United States of America, residing at Walnut Park, California, in the county of Los Angeles and the State of California, have invented a new, original, and ornamental Design for a Plate or Similar Article, of which the following is a specification, reference being had to the accompanying drawing, forming part thereof.

The figure is a plan view of a plate, showing my new design.

The dominant features of my design reside in the portions shown in full lines.

I claim:

The ornamental design for a plate or similar article, as shown and described.

GEORGE A. BAKER.
